UNITED STATES PATENT OFFICE.

CHARLES F. KETTERING AND WILLIAM A. CHRYST, OF DAYTON, OHIO, ASSIGNORS TO THE DAYTON ENGINEERING LABORATORIES COMPANY, A CORPORATION OF OHIO

IGNITION APPARATUS.

Original application filed October 4, 1915, Serial No. 55,160. Divided and this application filed September 16, 1918. Serial No. 254,175.

To all whom it may concern:

- Be it known that we, CHARLES F. KETTERING and WILLIAM A. CHRYST, citizens of the United States, residing at Dayton, county of Montgomery and State of Ohio, have invented certain new and useful Improvements in Ignition Apparatus, of which the following is a full, clear, and exact description.
- 10 This invention relates to ignition timing and distributing devices for internal combustion engines and the like, and particularly to the type of apparatus disclosed in our patent No. 1,303,831, dated May 13, 1919, of which this application is a division.
- One of the objects of this invention is to provide an ignition unit, wherein the time of occurrence of the sparking impulses in the ignition circuits may be automatically controlled, or may be manually or mechanically controlled, as may be desirable.
- It is a further object of the present invention to combine the automatic control of the ignition system in such a manner that 25 this type of control will automatically actuate the timer cam, and the rotor of the distributor, by the movement of these parts, relative to the timer contacts and the distributing contacts, respectively, in combination with a manually operated control which is arranged to actuate the timer contacts and the distributor contacts, relative to the timer cam and the rotor of the distributor.
- 30 A further object is to provide an ignition timing and distributing unit in which the construction is greatly simplified in order to reduce the amount of material and the cost of manufacture.
- 40 A further object is to provide an ignition timing and distributing unit in which the construction has been standardized in order that many parts will be common to a series of such units which may differ from one another in order to suit the requirements of different engines.
- Further objects and advantages of the present invention will be apparent from the following description, reference being had to the accompanying drawing, wherein 45 a preferred embodiment of the present invention is clearly shown.
- In the drawings:—
- Fig. 1 is a view in elevation of a timing and distributing unit for the ignition system embodied in the present invention, certain of the parts of this unit being shown in section for the sake of clearness.
- Fig. 2 is a top plan view of the unit disclosed in Fig. 1, with the distributor head 55 and the casing, carrying the timer contacts and rotor of the distributor, removed to more clearly disclose the centrifugal governor or control.
- Fig. 3 is a top plan view similar to Fig. 65 2, with the casing carrying the timer contacts and showing the timer cam in position.
- Figs. 4 and 5 are detail views of certain 70 of the elements embodied in the ignition unit.
- By referring to the drawings, it will be seen that a shaft 257 extends into a casing 258, but this shaft is operable relative to said casing, and is not connected thereto. The shaft 257 may be termed the driving 75 shaft of the ignition unit, but it is not thought necessary to describe or illustrate the driving connections between this shaft and the engine actuated parts, inasmuch as these connections are clearly described 80 in our patent No. 1,229,754, dated June 12, 1917.
- This shaft is pinned to a collar 259, by means of the pin 290, said collar being formed integral with or secured to the disc 261. 85 This disc or plate 261 carries a plurality of pins 260, which form pivotal mountings for weight elements 262, see Figs. 1 and 2 particularly. Each of these weights is preferably made up of a number of different 90 punchings or formed pieces, as is clearly shown in Fig. 1, but, of course, may be made of a single solid piece if so desired.
- By using fabricated weight elements formed by a series of punchings, it is possible to vary the mass of the weight elements simply by varying the number of punchings. Therefore in constructing ignition units to meet different engine requirements, the weight members employed 100 can be constructed from punchings of the same size.
- The free ends of the respective weight elements are connected to the disc 261, by

means of the resilient or flexible connections 263, which in the present instance constitute coil springs. One end of each of these springs is secured to a pin 264, carried by 5 the weight elements, while the opposite ends of said springs are connected to points 265, which are carried by the disc 261. These springs normally maintain the 10 weights in what may be termed closed position. Each of the weight elements are provided in turn with a flanged portion or bottom plate 266, provided with a notch 267, which is adapted to receive an arm 270 of the spider 272, see Figs. 2 and 4.

15 This spider forms the carrying element for the timer cam 268, and the rotor 269 of the distributor.

By referring to Fig. 3, the relative location of the timer cam 268 and the timer 20 contacts is clearly shown, while in Fig. 1, the relative location of the rotor of the distributor and the distributor contacts is clearly shown.

The spider 272, shown in detail in Fig. 4, 25 comprises a plurality of arms 270, so spaced as to readily engage within the notches 267 formed in the weights 262, each of these arms having an enlarged rounded end portion to snugly fit within the notch formed 30 in the weight, and still readily permit movement of the weight relative to the arm. This spider is connected to the driving shaft 257 solely by its connection above described, with each of the weight elements 262.

35 The upper end of the spider is provided with a reduced portion 271, which carries the timer cam 268 and the rotor of the distributor, as described hereinafter.

The casing 258 which contains the 40 elements heretofore described, and through which the shaft 257 passes, is provided with a sleeve 273 having a flange portion 274, said sleeve surrounding the shaft 257 and being connected to the casing 258, by means of 45 fastening bolts or rivets 275, which also secure a suitable handle or operating rod 276 rigidly to the casing.

From the above description, the operation 50 of the device shown in Figs. 1 to 5 inclusive, will be as follows:

When the engine or other driving means actuates the shaft 257, the disc 261, the weight elements 262 and the spider 272 which carries the timer cam and rotor of the distributor will all turn the rod concomitantly with the shaft 257.

Now, as the speed of this shaft increases, which of course is the equivalent to the speed of the engine increasing, the weight elements 60 262, under the effect of centrifugal force, will tend to fly apart, against the tension of the springs 263. The movement of the weights 262, due to the effect of centrifugal force, will be transmitted to the timer cam and rotor of the distributor, through the

connection of the weights with the spider element 272.

It will therefore be seen that as the weights move outwardly, the timer cam will be moved relative to the timer contacts and will therefore effect an advance in the time of closing the primary circuit of the ignition system, and inasmuch as the rotor of the distributor is carried by the same member as the timer cam, the time of closing the secondary circuits by the operation of the rotor of the distributor, relative to the distributor contacts, will be advanced or moved in exactly the same proportion as the timer cam.

However, it will be appreciated that under certain conditions, it may be desirable to manually control the time of occurrence of the sparking impulses, and in the present instance, this is effected by connecting the casing which carries the distributor contacts 85 and the timer contacts with a controlling member which may be readily actuated by the operator, to advance or retard the time of occurrence of the sparking impulses.

The timer contacts are mounted within 90 a cup 277, which fits within the casing 258, and is secured thereto in any suitable manner by means of a bayonet joint construction. This cup is prevented from movement relative to the outer casing, not only by means 95 of this bayonet joint construction, but also by providing a spring 278, one end of which projects through an opening formed in this inner casing, pressing against the inner face of the outer casing as at 278. The 100 opposite end of said spring is connected to the movable contact element 279, which is adapted to be moved into and out of contact with the fixed contact 280, and thereby controls the making and breaking of the primary 105 circuit of the ignition circuit.

This movable contact element comprises 110 a plate 281, formed to provide a pair of lugs 282, between which the contact roller 283 is suitably positioned. From the above, it will be seen that the spring 278 not only tends 115 to prevent relative movement between the cup 277 and the outer casing 258, but it also tends to maintain the movable contact plate 281 in engagement with the stationary contact point 280, except when the same is actuated by the lobes of the timer cam.

By providing a timer cup which is readily removable from the timer casing, repair and replacement of units and parts of the apparatus are facilitated.

While the form of mechanism shown and described constitutes a preferred form of embodiment of the present invention, it is to be understood that other forms might be adopted, all coming within the scope of the claims which follow:

1. In an ignition timer, the combination 120 with a casing and a drive shaft supported for rotation thereby; of a disc mounted on 130

said shaft; a plurality of laminated weight members pivotally mounted on said disc, each weight member having a bottom plate adjacent the disc provided with a notch and 5 other plates mounted on said bottom plate; springs restraining movement of the weights located below the disc; a cam support mounted for rotation within the casing and having arms located in the plane of 10 the bottom plates of the weight members, each arm being received by one of said notches; a timer cam mounted on the cam support above the weight members; breaker mechanism controlled by the cam; and a 15 support for the breaker mechanism located between the cam and weights.

2. In an ignition timer, the combination with a casing and a drive shaft supported for rotation thereby; of a disc mounted on 20 said shaft; a plurality of weight members pivotally mounted on said disc, and each provided with a notch located below the top surface of the weight; springs for restraining movement of the weights located below 25 the disc; breaker mechanism located above the weights; a support for said mechanism located closely adjacent the weight members; a cam support including arms cooperating with said notches and rotatably

mounted within the casing; and a cam 30 mounted on the cam support above the breaker support.

3. In an ignition timer, the combination with a casing and a drive shaft supported for rotation thereby; of a disc mounted on 35 said shaft; a plurality of weight members mounted on said disc; springs for restraining the weight members; a breaker support located above the weight members; a bearing mounted on the breaker support; a cam support cooperating with the weight members below the breaker support and journaled upon said bearing; a cam mounted on the cam support above the breaker support; and breaker mechanism mounted on said breaker 40 support; said breaker support being removable from the casing without disturbing the weights and springs, and carrying with it the cam and cam support all in assembled 45 relation.

In testimony whereof we affix our signatures.

CHARLES F. KETTERING.
WILLIAM A. CHRYST.
